UNITED STATES PATENT OFFICE

JOHN T. PRITCHARD, OF NEWARK, NEW JERSEY.

ROTARY IMPACT-MOTOR.

No. 852,293.

Specification of Letters Patent.

Patented April 30, 1907.

Application filed September 2, 1904. Serial No. 223,148.

To all whom it may concern:

Be it known that I, JOHN T. PRITCHARD, a citizen of the United States, residing at No. 20 Astor street, Newark, in the county of Essex and State of New Jersey, have invented certain new and useful Improvements in Rotary Impact-Motors, of which the following is a specification.

My invention relates to motors employing a rotary piston or wheel upon which the motive fluid, whether of gaseous or liquid nature, acts by impact and reaction, and has for its object to increase the efficiency of such a motor by the use of a novel form of wheel or rotating piston, the novelty consisting particularly in the peculiar construction and arrangement of the buckets, pockets or recesses disposed at the periphery of the wheel and into which the motive fluid is discharged.

Other improvements are embodied in my invention and will be hereinafter described.

Figure 1 is a side elevation of a motor embodying my improvements, a part of the casing being broken away and the nozzle being in vertical section. Fig. 2 is a vertical sectional view taken on the line 2--2 of Fig. 1. Fig. 3 is a perspective view, enlarged, of a small portion of the adjacent parts that together constitute the wheel or rotary piston of the motor, the parts being separated to show their construction. Fig. 4 is an edge view of a small section of the rotary wheel or piston. Fig. 5 is an elevation, parts being in section, of the valve controlling the inlet passage to the motor. Fig. 6 is a detached perspective view of the adjustable member of the valve. Fig. 7 is a transverse sectional view of the valve taken on the line 7--7 of Fig. 5.

The impact wheel or rotary piston of the motor is provided with a series of peripherally arranged buckets or pockets into which is discharged the motive fluid from a nozzle arranged tangentially, or approximately so, to the wheel and opposite the periphery thereof, and as close thereto as possible. The motive fluid after being delivered to the wheel and having performed its office in the rotation thereof, is quickly discharged.

In the drawings 2 designates the casing in which the rotary wheel or piston of the motor is mounted. A nozzle 3 enters the casing and through it is delivered the fluid that acts upon the wheel. This fluid may be obtained from any suitable source. It may be a liquid delivered from a reservoir so situated as to

impart to the liquid the necessary velocity as it issues from the nozzle; or it may be steam delivered from any suitable source of supply; or it may be any other gaseous body, such as 60 the products produced by the burning of a hydrocarbon gas. The source of supply of the fluid that passes through the nozzle is immaterial so far as my invention is concerned. The rotary piston or wheel is 65 mounted upon a shaft 4 from which the power developed by the motor is taken and utilized. The wheel consists essentially of a hub 5 secured to the shaft, a web portion 6, and a rim portion 7. In the latter are formed 70 the buckets, pockets, or recesses 8 into which the motive fluid is discharged. These are separated from each other and partially formed by division walls 9 that are preferably formed integral with the rim portion 7 of the 75 wheel. The disposition and arrangement of the division walls separating the buckets or pockets is peculiar, each wall being formed of two parts that are preferably of equal length and converge from the opposite sides of the 80 wheel, the line where they meet being situated in the central transverse plane of the wheel. I have found that the best results are obtained when the two parts of the division walls are disposed at an angle of approximately 45 degrees to each other. The division walls do not extend out radially, but are rather inclined backward, that is, in a direction opposite to that in which the wheel turns, and the inclination that I have found 85 to give the best result is of approximately 90 22½ degrees.

The division walls are arranged quite close to each other and preferably taper from their bases outward. As already stated, the division walls 9 are preferably integral with the flange portion of the wheel in order to give the necessary strength and they may be formed by milling machinery, such as is employed in cutting teeth in gearing.

In order to produce a wheel such as I have described, that is with the walls that separate the peripheral buckets inclined and formed of converging portions, as stated, by the use of milling machinery, I have found it 95 desirable to make the wheel of two parts, each part carrying only those portions of the division walls that incline transversely in one direction. The two parts are brought together and securely united by bolts 10, or other uniting means, the line of union being the central plane of the wheel, where the two 100 105 110

converging parts of the division walls meet. The wheel or rotary piston is provided with a pair of annular side flanges 11—11, suitably secured to the rim portion of the wheel and arranged to close the pockets 8 at their sides. These flanges extend outward for a short distance beyond the peripheral edges of the division walls 9, and the delivery end of the nozzle 3 is disposed between them.

14 indicates the discharge through which the motive fluid, after having acted upon the wheel, is delivered.

It is desirable that the pressure at the discharge 14 should be as low as possible in order that the reactive force of the motive fluid on leaving the wheel shall be correspondingly high. I therefore find it desirable under some circumstances to arrange an exhaust device in connection with the discharge passage of the motor. For the purpose of illustration, I have represented this exhaust device as consisting of a fan 16 that may be driven from any suitable sort of power, it being represented as geared to and driven from the shaft 4 of the motor.

In order to control the delivery of the motive fluid to the nozzle 3 I make use of two valves, a controlling valve 17, which may be of any usual or preferred construction, and a cut-off valve 18. The latter is situated within a three-way section of the supply pipe, one branch, 19, of which leads from the main supply pipe 20 directly to the nozzle, while the other branch 21 leads into the open air, condenser, or to any other desired place away from the motor. The valve 18 is a leaf-valve arranged to lie across the entrance to either of the branches 20—21 of the three-way section, accordingly as it is adjusted, and is so shaped that the steam passage is unobstructed and free in whichever position it may be set. To secure this one face, 30, of the valve is curved on an arc corresponding with that uniting the fluid passages 20 and 19, while the other face, 31, is straight or corresponding with the direction of the passage between the passages 20 and 21. The three-way connection in which is situated the valve 18 is formed of two parts 32, 32, separated along the central longitudinal plane of the connection, taken as a whole, and suitably united after the valve has been fitted to its seats. In each part 32 is formed a flat seat 33 against which one side edge of the valve moves. The outer end or edge 34 of the valve is curved and is arranged to be seated against curved valve seats 35, situated on opposite sides of the fluid passage 20 and formed one half in each section 32. This construction of valve 55 may be worked easily and quickly, is steam tight, and causes an easy and smooth flow whichever way it may be set.

I propose to use my motor for propelling automobiles and to generate the motive fluid by the combustion of charges of a hydrocar-

bon vapor. In such cases there might be sparks or incandescent gases discharged from the wheel, though I consider this to be unlikely. Therefore to guard against all possibility of danger from fire due to the heated condition of the discharge from the wheel, I propose to form an opening 36 in the casing, which may be of funnel shape or to which a funnel attachment may be applied, so that the forward movement of the vehicle will cause large quantities of air to mingle with the gases discharged from the wheel to cool them below the danger point. The casing may, if found desirable, be arranged in close proximity to the peripheral edges of the division wall 9, between the flanges 11, for a suitable distance beginning at a point just in front of the nozzle, though I do not wish to be limited to this feature of construction. Nor do I wish to be limited to the exact shape of the buckets and separating division walls illustrated. The angle at which they are set on the periphery of the wheel may be varied within certain limits, and the relation of the two parts of the division walls which converge toward the transverse center of the wheel with reference to each other may be changed within certain limits from that shown. It is however important that the division walls between the buckets should be inclined backward and that each should be formed of two parts which converge from the opposite sides of the wheel toward the transverse center thereof. Such a wheel when used in connection with a supply nozzle that delivers peripherally and with a discharge passage from which the motive fluid is delivered peripherally from the wheel has been found to develop great power and to be an exceedingly efficient element of a motor.

I have shown the motor as provided with but one nozzle 3, as this fully illustrates my invention, but I do not wish thereby to limit my invention to such a motor, as the number of nozzles employed may be increased if experience shows this to be desirable.

What I claim is:

1. A wheel or piston for an impact rotary motor provided with a series of peripheral buckets whose division walls incline rearward and are each composed of two parts that converge from the opposite sides of the wheel toward the transverse central plane thereof, substantially as set forth.

2. A wheel or piston for an impact rotary motor provided with a series of peripheral buckets separated from each other by division walls, which walls incline rearward at approximately an angle of $22\frac{1}{2}$ degrees and each of which is formed of two parts disposed approximately at an angle of 45 degrees to each other, their meeting edges being in the central transverse plane of the wheel, substantially as set forth.

3. In a motor of the rotary impact type

arranged to be driven by highly heated gases, the combination of the rotary wheel, the nozzle, and the casing provided with a discharge passage for the gases after they have acted 5 on the wheel, and an air passage 36 adjacent to the discharge passage through which air may be passed to mix with the discharged gases to cool the same, the outer larger end of said passage being adapted to be left open 10 to the atmosphere, substantially as set forth.

4. In a rotary impact motor, the combination of the wheel, the nozzle, a three-way connection, one branch thereof being connected with the supply pipe and another 15 with the nozzle, and the connection being formed of two parts, the plane of separation between them being at the central longitudinal plane of the connection considered as a whole, and 20 a valve arranged within the three-way connection for diverting the supply either to the nozzle or away therefrom, substantially as set forth.

5. In a rotary impact motor, the combination of the wheel, the nozzle, a three-way connection, one branch thereof being connected with the supply pipe and another with the nozzle, the connection being formed of two parts, the plane of separation between them being at the central longitudinal plane of the connection considered as a whole, and 25 there being formed in each part of the connection valve seats 33, 35, and a valve 30 within the connection fitted to the said valve seats, and having one face shaped to correspond with the direction of the fluid passage between the supply pipe and the branch that is united with the nozzle, and the other face shaped to correspond with the fluid passage between the supply pipe and the other branch, substantially as set forth.
